DESIGN FOR A DRESS

Paul Calick, New York, N. Y.

Application March 23, 1940, Serial No. 91,184

Term of patent 3½ years

To all whom it may concern:

Be it known that I, Paul Calick, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the printed dress disclosed of the specific shirring on the collar, cuffs, and pockets, which shirring constricts the material between the printed medallions and gives to the medallions a puffed appearance as shown.

I claim:

The ornamental design for a dress, substantially as shown and described.

PAUL CALICK.
